(57) **CLAIM**

The ornamental design for a point-of-sale terminal, as shown and described.

DESCRIPTION

FIG. 1 is a front, top, and right-side orthographic view of a point-of-sale terminal showing the new design.

FIG. 2 is a front elevation view of the point-of-sale terminal.

FIG. 3 is a right-side elevation view of the point-of-sale terminal.

FIG. 4 is a left-side elevation view of the point-of-sale terminal.

FIG. 5 is a rear elevation view of the point-of-sale terminal.

FIG. 6 is an enlarged top plan view of the point-of-sale terminal; and,

FIG. 7 is an enlarged bottom plan view of the point-of-sale terminal.

The broken lines shown in the drawings illustrate portions of the point-of-sale terminal that form no part of the claimed design.

1 Claim, 4 Drawing Sheets
